UNITED STATES PATENT OFFICE.

ROBERT MEYER AND JOSEPH PERRIN, OF COURS, FRANCE.

COMBING-CYLINDER FOR COMBING-MACHINES.

No. 798,913.

Specification of Letters Patent.

Patented Sept. 5, 1905.

Application filed October 13, 1904. Serial No. 228,283.

To all whom it may concern:

Be it known that we, ROBERT MEYER and JOSEPH PERRIN, engineers, citizens of the French Republic, residing at Cours, in the Department du Rhône, France, have invented new and useful Improvements in and Relating to Combing-Cylinders for Combing-Machines, of which the following is a specification.

This invention relates to a combing-cylinder which is applicable to combing-machines in general, and more particularly to machines of the Heilmann class for the combing of wool, silk, cotton, and other fibers.

It is known that with the needle-segment of combing-cylinders of large diameter already in use it has been necessary to employ complicated apparatus or devices to permit only the penetration of a portion of the fiber into the needles. On the other hand, in the Heilmann type of combing-machine having a segment of reduced radius the segment, by reason of its short periphery, will not be able to carry enough rows of needles to insure the proper combing of the fiber.

The combing-cylinder which is the subject of the present improvements combines the advantages of a cylinder of large diameter with the advantages of a cylinder of small diameter.

The improved combing-cylinder is illustrated in the accompanying drawings, of which—

Figure 1 shows the cylinder in vertical cross-section working in conjunction with a "nipper" of a machine of the Heilmann type. Fig. 2 illustrates it in longitudinal section. Modifications are represented in Figs. 3 and 4, in which Fig. 3 is a longitudinal sectional view of part of such a modified cylinder, and Fig. 4 represents the modified parts in end elevation working in conjunction with a nipper of any desired type.

1 is a cylinder or drum upon or within which are circularly disposed and arranged a convenient number of smaller combing-cylinders 2 3 4 5 6 7, which when the machine is in operation are preceded by a small segment of the drum 1, upon which reduced or small segment 8 are arranged rows of needles obliquely to lines on the drum parallel with the drum-axis. The pitch or setting of the needles upon the small needle-cylinders becomes progressively finer from 2 to 7, following the usual practice in combing machines. The smaller cylinders are mounted upon shafts 9.

The main cylinder 1 is keyed to a shaft 10, which is capable of giving to the complete cylinder and its parts a rotary motion in the direction of the arrow *x*. On the shafts 9 60 are secured pinions gearing with a central wheel 12 in such a manner that the rotation of the cylinder 1 in the direction of the arrow *x* causes the shafts 9 to rotate in the direction of the arrows *y*, the attached small cylinders 2 3 4 5 6 7 consequently rotating in the same direction of the arrow *y*.

The nipper 13 14 of the combing-machine is represented in its open position in dotted lines and in its closed position in full lines in Fig. 1 of the drawings. When it is in its closed position, the fiber of the "lap" 15 is submitted to the combing action of the coarse needles of the small or reduced segment 8 first, then successively to the graduated action of the small cylinders 2 3 4 5 6 7 as the shaft 10 is rotated.

In addition to the common movement in the direction of the arrow *x* around the center of the drum 1 the smaller cylinders have also a 80 planetary movement imparted to them of rotation around their own axes in the direction of the arrows *y*, consequent upon the engagement of the pinions 11 with the wheel 12, which may be either fixed or moving. 85

When the lap is comparatively clear or free from short fibers or other impurities, a fixed wheel 12 may be used, as the length of the segment of each of the small cylinders which will then engage with the lap will be sufficient. 90 When, however, the lap requires considerable treatment, the wheel 12 instead of being fixed to the frame of the machine may also rotate. To effect this, it may be secured to a wheel 16, which may be driven by a pinion 17. When 95 desired, the wheel 12 may be driven in the direction of the arrow *z*, and thus cause an increased speed of rotation of the small cylinders around the axes in the direction of the arrows *y* and increase the combing action. 100 The wheel 12 may have its rotation continued or varied or discontinued by well-known mechanical means. With this arrangement a great range of combing action may be obtained. 105

With the devices illustrated in Figs. 1 and 2 the small cylinders have a continuous planetary motion imparted to them when the machine is in use, caused by the constant engagement of their pinions with the central fixed toothed wheel 12; but as the work effected by the small cylinders 2 3 4 5 6 7 may

be done by a length of arc or segment of such cylinders which is about equal to the length of the fiber under treatment the small cylinders may be so mounted as to rotate intermittently and only within the fiber. How the desired intermittent motion may be obtained is represented in Figs. 3 and 4 of the drawings. In this modification the toothed pinions formerly shown on the shafts of the small cylinders are replaced by four toothed wheels or star-wheels 25, which in conjunction with disks 26, having curved recesses formed on their peripheries, are secured to the shafts 18, which carry the small cylinders now indicated by the figures 19 20 21 22 23 24. 27 is a fixed disk, around the periphery of which one or other of the recessed faces of all the disks 26 slide and engage. An enlargement or recess in the disk 27 permits of the partial rotation of the disks 26 when desired. As the cylinder 1 rotates the whole of the small cylinders are carried round with it without rotating until they successively arrive at the section-finger 28, which is secured to a bracket 29, formed upon or attached to the sleeve or socket 30. Each star-wheel as it comes against the action-finger is successively turned thereby through a quarter of a revolution, carrying with it its attached small cylinder, either 19, 20, 21, 22, 23, or 24. Then the combing is accomplished by either of the two systems described, and the nippers 13 and 14 move in the known manner and open, as indicated by the broken lines, to permit the passage of the "sliver," which is seized by the fluted gripping or drawing rollers 31 and 32. The tail of the fiber not combed traverses the upper rectilinear comb 33.

The lubrication of the bearings of the small combing-cylinders is effected by the contact of their bearing-surfaces with wicks 34, soaked with lubricant and lodged in wells formed in the cylinder 1.

35 indicates a clearing-brush.

Having now particularly described and ascertained the nature of our said invention and in what manner the same is to be performed, we declare that what we claim is—

1. In a combing-cylinder, the combination of a rotatable drum having combing-teeth arranged on a segment of the periphery, a circular series of combing-cylinders rotatably supported on the drum with their axes parallel with the drum-axis and their peripheries intersecting the periphery of the drum, means for rotating the drum, and means for moving the cylinders on their axes.

2. In a combing-cylinder, the combination of a rotatable drum having combing-teeth arranged on a segment of the periphery, a circular series of combing-cylinders rotatably supported on the drum with their axes parallel with the drum-axis and their peripheries intersecting the periphery of the drum, means

for holding the fiber in position to be engaged by said segment-teeth, and means for turning the drum to bring the segment-teeth and the cylinders successively into engagement with the fiber.

3. In a combing-cylinder, the combination of a rotatable drum having combing-teeth arranged on a segment of the periphery, a circular series of combing-cylinders rotatably supported on the drum with their axes parallel with the drum-axis and their peripheries intersecting the periphery of the drum, means for holding the fiber in position to be engaged by said segment-teeth, and means for turning the drum to bring the segment-teeth and the cylinders successively into engagement with the fiber, and means for turning the cylinders on their axes when carried by the drum into said position of engagement with the fiber.

4. In a combing-cylinder, the combination of a rotatable drum having combing-teeth arranged on a segment of the periphery, a circular series of combing-cylinders rotatably supported on the drum with their axes parallel with the drum-axis and their peripheries intersecting the periphery of the drum, means for holding the fiber in position to be engaged by said segment-teeth, and means for turning the drum to bring the segment-teeth and the cylinders successively into engagement with the fiber, and means for turning the cylinders on their axes when carried by the drum into said position of engagement with the fiber, and means for holding the cylinders stationary on their axes except when in said position engaging the fiber.

5. In a combing-cylinder, the combination of a rotatable drum having combing-teeth arranged on a segment of the periphery, a circular series of combing-cylinders rotatably supported on the drum with their axes parallel with the drum-axis and their peripheries intersecting the periphery of the drum, means for holding the fiber in position to be engaged by said segment-teeth, and means for turning the drum to bring the segment-teeth and the cylinders successively into engagement with the fiber, a toothed wheel on each cylinder-axis, a stationary detent arranged to engage and turn each toothed wheel as its cylinder reaches the fiber, a stationary disk, a disk on each cylinder having recesses normally engaging the stationary disk and preventing axial movement of the cylinders, the stationary disk having a peripheral recess arranged to permit said turning of each cylinder by the toothed wheel when engaging the fiber.

6. In a combing-cylinder, the combination of a rotatable drum having a circular series of combing-cylinders rotatably supported thereon, with their axes parallel with the drum-axis and equidistant therefrom, the successive combing-cylinders having their teeth becom-

ing progressively finer in pitch, means for turning the drum, and means for moving the cylinders on their axes.

7. In a combing-cylinder, the combination of a rotatable drum having a circular series of combing-cylinders rotatably supported thereon, with their axes parallel with the drum-axis and equidistant therefrom, the successive combing-cylinders having their teeth becoming progressively finer in pitch, means for turning the drum, means for holding the fiber in a position to be successively engaged by the teeth of the cylinders when the drum is turned, and means for turning the cylinders on their axes when moved by the drum into engagement with the fiber.

8. In a combing-cylinder, the combination of a rotatable drum having a circular series of combing-cylinders rotatably supported thereon, with their axes parallel with the drum-axis and equidistant therefrom, the successive combing-cylinders having their teeth becoming progressively finer in pitch, means for turning the drum, means for holding the fiber in a position to be successively engaged by the teeth of the cylinders when the drum is turned, and means for turning the cylinders on their axes when moved by the drum into engagement with the fiber, and means for holding the cylinders stationary on their axes except when in said position engaging the fiber.

9. In a combing-cylinder, the combination of a rotatable drum having a circular series of combing-cylinders rotatably supported thereon, with their axes parallel with the drum-axis and equidistant therefrom, the successive combing-cylinders having their teeth becoming progressively finer in pitch, means for turning the drum, means for holding the fiber in a position to be successively engaged by the teeth of the cylinders when the drum is turned, and means for turning the cylinders on their axes when moved by the drum into engagement with the fiber.

35 40 45 50 55

in a position to be successively engaged by the teeth of the cylinders when the drum is turned, and means for turning the cylinders on their axes when moved by the drum into engagement with the fiber.

In testimony whereof we have signed our names to this specification in the presence of two subscribing witnesses.
